ION TRAP ELECTRON GUN FOR CATHODE RAY TUBES

Kenneth A. Hoagland, Newark, N. J., assignor to Allen B. Du Mont Laboratories, Inc., Clifton, N. J., a corporation of Delaware

Application October 1, 1951, Serial No. 249,120

14 Claims. (Cl. 313—82)

The present invention relates to cathode ray tubes and more particularly to improvements in cathode ray tube ion trapping devices of the type disclosed in U. S. Patent 2,637,828, issued May 5, 1953, assigned to the assignee of the present invention.

In the device disclosed in that application, the ion trapping anode is in the form of a tubular member having adjoining axially inclined tubular portions. While the anode in this form is completely effective as an ion trapping means, its bent configuration places unnecessary dimensional limitations on the length and diameter of the neck portion of a cathode ray tube in which it is assembled.

Accordingly, it is an object of the present invention to provide an improved ion trapping electron gun for cathode ray tubes.

It is a further object of this invention to provide an electron gun eliminating unnecessary dimensional limitations of the neck portion of the cathode ray tube.

Further objects and features of the invention will be apparent as the description of the invention proceeds in conjunction with the drawing in which:

Fig. 1 is a fragmentary view partly in cross-section of a cathode ray tube illustrating the improved ion trapping electron gun of this invention.

Figure 2 is an enlarged fragmentary view in cross-section of the ion trapping electron gun illustrated in Figure 1 and

Figure 3 is an enlarged fragmentary view in cross-section of one modification of the ion trapping device of this invention.

Referring now to the drawing, and particularly to Fig. 1, there is illustrated the neck 2 and base 4 of a cathode ray tube, the enlarged bulb and screen supporting face of which are not shown. Supported within the neck 2 there is an ion trapping electron gun of the type commonly known as a bent gun type; such a type being fully described in my above-referred to application.

The electron gun comprises a cathode-grid assembly 6, a second grid 8 and an accelerating anode-focussing electrode assembly 10 secured together in spaced relationship along the longitudinal axis of the neck 2.

As shown in Fig. 2, the cathode-grid assembly 6 includes a tubular cathode member 10 supported coaxially within a thimble-shaped grid member 12 having a coaxially aligned aperture 14 by an insulating disc 16. A suitable electron emissive material 18 formed on the end of the cathode and a spirally formed heater coil 20 suitably insulated and contained within the cathode member 10 provides a source of electrons for the cathode ray tube.

The second grid 8, as illustrated in Fig. 2 is a cup-shaped member having an axially aligned aperture 21 and an outwardly extending rolled flange 22 provided with diametrically disposed ears 24, see Fig. 1. The accelerating anode focussing assembly 10 which forms the remaining unit of the electron gun assembly comprises a preaccelerating anode 26, a focussing electrode 28 and

an accelerating anode 30. As shown in Figures 1 and 2, the preaccelerating anode is formed of a tubular metal member having a reduced or spherical end portion 32 terminating in an aperture 34 formed in a plane inclined to the central axis of the member and perpendicular to the axis of alignment of the cathode-grid assembly 6 and grid 8. The accelerating anode 30 is likewise a tubular metal member of substantially the same diameter as the preaccelerating anode 26 and is formed at one end thereof with a radially extending flange 36, an arcuate edge portion of which is received in slots 38 of a pair of opposite disposed spring fingers 40. The end surfaces of the spring fingers 40 engage an electrical conductive coating 41 on the inner surface of the neck 4 to provide electrical contact between the anode 30 and a terminal member not shown which is connected to the electrical conductive coating 41. The spring fingers 40 also provide means for supporting one end of the electron gun structure in axial alignment within the neck 4 of the cathode ray tube. Positioned between the preaccelerating anode 26 and the accelerating anode 30 is a focussing electrode 28 in the form of a tubular metal member having a substantially larger diameter than the diameters of the preaccelerating anode 26 and the anode 30. The preaccelerating anode 26, focussing electrode 28, and anode 30 are assembled as a unit in coaxial alignment, as shown, by providing a plurality of circumferentially spaced glass insulating rods 42 into which are sealed the ends of a plurality of circumferentially spaced pins 44 extending radially from and attached to the respective anodes and electrode. An accelerating anode-focussing electrode assembly similar to the one hereinabove described along with its function is disclosed in detail in my application Serial No. 235,010, filed July 3, 1951, and assigned to the assignee of the present invention.

In assembling the electron gun to provide means for trapping undesirable ions, strap 46 is secured to the outer cylindrical surface of the preaccelerating anode 26 as shown. The strap 46 is provided with tubular end portions 48 disposed on opposite sides of the anode 26 and adapted to receive rods 50 of insulating material. The axes of the tubular end portions 48 are inclined to the central axis of anode 26, focussing electrode 28, and anode 30, and are perpendicular to the plane of the aperture 34 in the reduced end portion 32 of anode 26. With the rods 50 disposed in the manner described, the second grid 8 is positioned between the rods by means of passing the rods through apertures, not shown, in the ears 24 of the grid 8. The grid 8 is thereafter secured in position by means of tubular members 52 which are likewise passed over the rods and secured to the ears 24 by any suitable means such as welding. Thereafter, the cathode grid assembly 6 is positioned between the rods and secured in position by a strap 54 which surrounds the cathode grid assembly and is formed with oppositely disposed tubular portions 56 adapted to receive the ends of the rods 50. With the cathode grid assembly 6 in position adjacent the grid 8, the oppositely disposed tubular portions are clinched on the rods. In assembling the grid 8 and cathode grid assembly 6 with the accelerating anode-focussing electrode assembly 10, the grid 8 and cathode-grid assembly 6 are spaced along a common axis with the grid 8 in juxtaposition to the reduced end of the preaccelerating anode 26. In providing such an alignment, the common axis of the cathode-grid assembly 6 and the grid 8 is perpendicular to a plane which passes through the aperture 34 in the reduced or spherical end portion 32.

With the electron gun structure assembled in the neck 70 of the tube, the cathode-grid end of the electron gun structure is supported in the neck of the tube by lead wires

55 connected through the base 4 to prong type terminals 57.

Referring now to Fig. 3, there is illustrated another form of preaccelerating anode embodying my invention in which an aperture 58 is formed in the spherical end portion 60 of a cylindrical cap 62; the cap being received and secured on the end of a tubular member 64.

In operation, electrons are released from the electron emissive material 18 and are constricted into a bundle in passing through the apertures 14 and 21 respectively. Thereafter, they are accelerated along the common axis of the cathode-grid assembly 6 and grid 8 through the aperture 34 of the preaccelerating anode 26 and into the space defined by the preaccelerating anode. Within the preaccelerating anode 26, any ions which are released at the cathode and carried along in the stream of electrons are separated from the electrons in a manner such as described in my first application mentioned hereinabove. The electrons are then focussed by the action of the focussing electrode 28 and are finally accelerated toward the screen of the cathode ray tube by the accelerating anode 30. In this connection, it will be understood that while I have described my invention in connection with an electrostatically focussed electrode such as described in the later of my abovementioned applications, it will be 25 equally as useful in electron gun structures in which focussing of the electrons is obtained by electromagnetic means.

In an electron gun structure such as I have hereinabove described, the preaccelerating anode 26 permits 30 an axial dimensional reduction of the tube as well as a reduction of the diameter of the neck thereof. The anode 26 with the reduced or spherical end portion and the aperture therein permits the spacing of the second grid adjacent thereto without an intermediate bent or axially incined tubular portion as has been the practice heretofore in the so-called bent gun structural types. Further, an ion trapping anode structure such as I have hereinbefore described lends itself to simple, inexpensive, 40 fabricating process and, because of its spherical end portion, eliminates the need of additional parts such as rolls in the anode structure or corona rings which are necessary to prevent excessive breakdown or stray emission from the lower potential electrodes of the assembly. Still further, an ion trapping anode such as I have described hereinabove in connection with an electron gun assembly 45 provides a symmetrical electrostatic field about the common axis of the cathode-grid assembly wherein lack of symmetry between the adjacent grid and anode would result in undesirable distortion of the electron beam.

While I have described preferred forms of my invention, it will be apparent that other forms may be used, all of which are intended to come within the scope of the claims which follow.

What I claim as new and desire to obtain by Letters Patent of the United States is:

1. In a cathode ray tube, a cathode and a grid aligned on a common axis and an anode aligned on a second axis inclined to said common axis, said anode having a spherical end portion with an aperture therein facing said cathode and grid, said aperture being formed in a plane perpendicular to said common axis said second axis passing through said end portion.

2. In a cathode ray tube, a cathode and grid aligned on a common axis and an anode aligned on a second axis inclined to said common axis, said anode having a spherical end portion adjacent said grid and an aperture formed in said spherical end portion in a plane perpendicular to said common axis said second axis passing through said end portion.

3. In an electron gun, a cathode and a grid aligned on a common axis, an anode aligned on a second axis inclined to said common axis, said anode having a spherical end portion with an aperture therein, said aperture being in a plane perpendicular to said common axis said axis passing through said end portion.

4. An anode for electron guns, said anode comprising a straight tubular portion having a spherical end portion with an aperture therein aligned in a plane inclined to the axis of said tubular portion.

5. In a cathode ray tube, a cathode, a first grid and a second grid aligned on a common axis and a preaccelerating electrode, a focussing electrode and an accelerating electrode aligned in spaced relationship on a second common axis inclined to said first-mentioned common axis, said preaccelerating anode having a spherical end portion facing said second grid, said end portion having an aperture therein formed in a plane perpendicular to said first-mentioned common axis said second common axis intersecting said end portion.

6. In a cathode ray tube having a grid and a straight tubular accelerating anode in juxtaposition with the axes of said grid and anode inclined to each other, said anode having a reduced end portion and an aperture therein, said aperture being formed in a plane perpendicular to the axis of said grid and at an acute angle to the axis of said tubular anode.

7. An anode for electron guns, said anode comprising a straight tubular portion having a hemispherical reduced end portion with an aperture therein aligned in a plane inclined to the longitudinal axis of said tubular portion.

8. In an electron gun having a grid and an accelerating anode in juxtaposition with the axes of proximal parts said grid and anode inclined to each other, said anode having a reduced end portion with an aperture therein, said aperture being formed in a plane perpendicular to the axis of said grid.

9. An anode for electron guns, said anode comprising a straight tubular portion and a cap secured to the end thereof, said cap having a hemispherical reduced end portion with an aperture therein aligned in a plane inclined to the longitudinal axis of said tubular portion.

10. In a cathode ray tube, a cathode and a grid aligned on substantially a common axis and an anode aligned on an axis inclined to said common axis, said anode comprising a straight tubular member having a reduced end portion completely contained within the axial projection of the wall of said tubular member, said end portion having an aperture therein of less cross-sectional area than the cross-sectional area of said tubular member and with the reduced end portion edge surrounding said aperture substantially in a plane which is inclined to the longitudinal axis of said tubular member and substantially normal to said common axis.

11. In a cathode ray tube, a cathode and a grid aligned on substantially a common axis and an anode aligned on an axis inclined to said common axis, said anode comprising a straight tubular member having a substantially spherical end portion completely contained within the axial projection of the wall of said tubular member, said end portion having an aperture therein of less cross-sectional area than the cross-sectional area of said tubular member with the central axis of said aperture inclined to the longitudinal axis of said tubular member and substantially in alignment with said common axis.

12. In a cathode ray tube, a cathode and grid aligned on substantially a common axis and an anode aligned on an axis inclined to said common axis, said anode comprising a straight tubular member having a substantially spherical end portion completely contained within the axial projection of the wall of said tubular member, said end portion having a circular aperture therein of less cross-sectional area than the cross-sectional area of said tubular member with the edge of said end portion defining said aperture in a plane inclined to the longitudinal axis of said tubular member and normal to said common axis.

13. In a cathode ray tube, an electrode comprising a straight tubular member having a hemispherical reduced end portion completely contained within the axial projection of the wall of said tubular member, said end portion having an aperture therein of less cross-sectional area than the cross-sectional area of said tubular member

with the edge of the reduced portion defining said aperture being substantially in a plane inclined to the axis of said tubular portion.

14. An electrode for cathode ray tube electron guns comprising a straight tubular member having a hemispherical reduced end portion completely contained within the axial projection of the wall of said tubular member, said end portion having an aperture therein of less cross-sectional area than the cross-sectional area of said tubular member with the edge of the reduced portion defining said aperture being substantially in a plane inclined to the axis of said tubular portion. 5 10
